United States Patent Office.

ROBERT A. GOODYEAR, OF BINGHAMTON, NEW YORK.

Letters Patent No. 91,738, dated June 22, 1869.

IMPROVED SPRING-BED BOTTOM.

The Schedule referred to in these Letters Patent and making part of the same.

To all whom it may concern:

Be it known that I, ROBERT A. GOODYEAR, of Binghamton, in the county of Broome, and State of New York, have invented and made a new and useful Improvement in Spring-Bed Bottoms; and I do hereby declare the following to be a full, clear, and exact description of the said invention, reference being had to the annexed drawing, making part of this specification, wherein—

Figure 1 is a side elevation, showing a portion of one of the slats of the bed-bottom; and

Figure 2 is a plan representing portions of three of such slats.

Similar letters denote the same parts.

In the manufacture of spring-bed bottoms, difficulty has been experienced from the weight coming only upon a portion of the slats, and causing the same to bend unduly or break, and efforts have been made to construct slats that would have a spring throughout their length of a nearly uniform character, but without success, as far as known, previous to my invention.

The nature of my said invention consists in a spring slat for bed-bottoms, formed of parallel-motion links, connecting the top and bottom slats, in combination with springs that act to keep the slats apart; the operation being that the slat receives a partial end-motion by the parallel links, as the springs are compressed, and hence, that the top slat moves throughout its length, parallel, or nearly so, to the standing bottom slat. By this construction, the weight of the person, upon any part of the slat, acts upon all the springs of that slat, in consequence of the parallel movement of the slat, as depressed; hence, the slats can be of thinner material than heretofore, and each

spring of less strength, because the weight is distributed by the parallel movement over a greater extent of surface.

In the drawing, *a* is the bottom slat; *b*, the top slat; *c c*, the parallel-motion links, hinged at 2 and 3, to the respective slats *a* and *b*; and *d* represents the spring.

These slats, *a* and *b*, are to be of any desired length, so as to lie longitudinally or transversely in the bedstead, or compose portions of sectional slats, more or less in number, set together to form the spring-bed bottom.

The slats *a* are to be sufficiently strong to bear the weight, or else they are to rest upon the usual slats of the bedstead.

The springs *d* are to be of any usual character, and should be attached to the slats, both at top and bottom.

The links *c c* are applied at suitable distances apart, along the slats, and are parallel to each other, and keep the slat *b* parallel to the slat *a*, as the former is depressed by any weight, in order that the action may be uniform, as aforesaid.

What I claim, and desire to secure by Letters Patent, is—

The parallel links *c c*, hinged, at their ends, to the top slat *b* and bottom slat *a*, in combination with the spring, or springs, intervening between said slats, as and for the purpose set forth.

In witness whereof, I have hereunto set my signature, this 18th day of May, A. D. 1869.

ROBERT A. GOODYEAR.

Witnesses:

CHAS. H. SMITH,

GEO. T. PINCKNEY.
